UNITED STATES PATENT OFFICE.

GEORGE P. GATES AND GEORGE THAUER, OF WATERTOWN, WISCONSIN.

ATTACHMENT FOR FORCE-FEED FAUCETS.

SPECIFICATION forming part of Letters Patent No. 562,892, dated June 30, 1896.

Application filed March 1, 1893. Serial No. 464,180. (No model.)

To all whom it may concern:

Be it known that we, GEORGE P. GATES and GEORGE THAUER, citizens of the United States, and residents of Watertown, in the county of Jefferson, and in the State of Wisconsin, have invented certain new and useful Improvements in Attachments for Force-Feed Faucets; and we do hereby declare that the following is a full, clear, and exact description thereof.

Our invention relates to attachments for force-feed faucets; and it consists in the matters hereinafter described, and pointed out in the appended claim.

15 In the accompanying drawings, Figure 1 is a central vertical sectional view of our improved device, showing the same applied to the discharge-spout of a force-feed faucet. Fig. 2 is a side elevation of our said device, 20 showing portions broken away to better illustrate the construction.

25 Referring by letter to said drawings, A designates the discharge-spout of a force-feed faucet, and B a tubular attachment adapted for detachable engagement therewith. This tubular part B is provided at its upper end with an enlarged socket B', having an interior, annular shoulder b. Set-screws C C are passed through the wall of the socket B' 30 and are arranged to engage with the spout A to hold the tubular extension in engagement therewith, said screws being conveniently arranged at an angle, as shown, so as to engage with the upper side of the usual annular flange a on the lower end of the spout A. A suitable packing-ring C' is interposed between the annular shoulder b and the lower end of the spout A, as shown, so as to afford 35 a tight joint between the spout A and the tubular extension B, the obliquely-arranged screws C C obviously serving to draw said tubular part upwardly toward said spout. A yoke D, comprising pendulous arms D'D', pivotally engaged at d d with the outside of 40 the tube B, and a cross-piece D², connecting the lower ends of said arms, is provided, said yoke being arranged to swing upon the connections d d, so as to bring the cross-piece D² beneath the lower end of the tube B to close 45 the same in an obvious manner.

50 As shown more particularly in Fig. 1, we prefer to make the lower end b' of the tube

B somewhat oblique, and we make the upper face of the cross-piece D² with a corresponding incline. We furthermore provide a suitable packing E, of leather or other suitable material, upon the inclined upper face of the cross-piece D², to which it is conveniently secured by a screw or rivet e. It follows from this construction that, when the yoke is moved 55 into a position to bring the cross-piece D² beneath the inclined or oblique lower end of the tube B, the packing E will be forced into engagement with said oblique end, and, by the oblique arrangement of said end and said 60 packing, a very tight joint will be effected. A suitable projection d' is conveniently provided at the side of the cross-piece D², which forms a convenient handle by which the yoke 65 may be operated and by means of which said 70 yoke may be held away from the tube when desired, said projection being adapted for engagement with any desired device for suspending the yoke in its open position.

We make the tubular extension B preferably somewhat tapering from top to bottom, the lower end being of such diameter as to enable it to be readily inserted in the neck F of an ordinary jug or bottle.

Great difficulty has heretofore been experienced in filling narrow-necked vessels, such as bottles or jugs, with syrups, thick oils, varnishes, and such substances by means of the ordinary force-feed faucets, from the fact that the discharge-spouts thereof are not 80 made of such a size as to be inserted in the necks of said vessels, and unless the discharge-spout or tube is thus inserted the thick viscid material will not flow into the narrow neck of the vessel which it is desired to fill. 85 It has therefore been a common practice to use a funnel for directing the syrup or other material into the vessel to be filled; but it has been found that where the material is fed into the vessel by gravity alone (as is the case 90 in using a funnel) the operation of filling the vessel is very tedious and unsatisfactory. It is to overcome this difficulty, and to render the operation of filling narrow-necked vessels 95 expeditious and easy, that we have devised 100 our improved attachment.

It will be seen that, by reason of the packed joint between the spout A and the tube B, there can be no leakage of the material at the

joint, and that when force is applied to expel the viscid materials they will be expelled through the contracted lower end of the tube B, and when said end is inserted in the neck 5 of a jug or bottle said material will be forced to pass directly into the said vessel. By means of the pivoted yoke with its obliquely-arranged packing, which engages with the oblique lower end of the tube, the said lower 10 end may be securely closed when desired.

Our improved device is very simple and strong in its construction and may be readily attached to any of the ordinary forms of force-feed faucets.

15 Having described our invention, what we claim as new, and desire to secure by Letters Patent, is—

In a force-feed faucet, the regularly-tapering tube A, provided with an enlarged upper 20 end, and having an annular flange a, at bottom, in combination with the detachable tubular part B, provided with a contracted

lower end with an oblique face, and having an enlarged perforated socket B', provided with an interior, annular, shoulder b; a series 25 of set-screws C, obliquely adjusted through the perforations in the wall of the socket, and abutting the flange a; the interposed packing C'; the pivotally-attached yoke D, comprising the pendulous arms D', and cross-piece D'; and the packing E, secured upon the upper face of the cross-piece, the latter provided with the projecting handle d', all constructed, arranged, and operating as hereinbefore described. 30

In testimony that we claim the foregoing we have hereunto set our hands, at Watertown, in the county of Jefferson and State of Wisconsin, in the presence of two witnesses.

GEORGE P. GATES.
GEORGE THAUER.
